UNITED STATES PATENT OFFICE.

CHARLES PEARSON, OF PHILADELPHIA, PENNSYLVANIA; SAID PEARSON AND HIS ADMINISTRATRIX (MARY PEARSON) ASSIGNORS TO JOHN DOBSON AND JAMES DOBSON, BOTH OF SAME PLACE.

PILE-CUTTING MECHANISM FOR DOUBLE-PILE-FABRIC LOOMS.

SPECIFICATION forming part of Letters Patent No. 394,606, dated December 18, 1888.

Application filed December 5, 1884. Serial No. 149,546. (No model.) Patented in England April 17, 1885, No. 4,766.

To all whom it may concern:

Be it known that I, CHARLES PEARSON, a subject of the Queen of Great Britain, at present residing in the city of Philadelphia, 5 in the State of Pennsylvania, have invented certain new and useful Improvements in Pile-Cutting Mechanism for Double-Pile-Fabric Looms, of which the following is a full, clear, and exact description, reference being had to 10 the accompanying drawings, forming a part of this specification, and for which I have obtained a patent in England, dated April 17, 1885, No. 4,766.

My invention relates to that part of the 15 mechanism of the loom used for severing the pile-threads of double pile fabrics woven in the well-known manner in two backings or cloths with intervening connecting pile-threads, so that when cut apart laterally 20 through the pile two distinct pieces of pile fabric are produced; and my invention consists in the construction and arrangement of the driving mechanism which reciprocates the knife-carriage, and in the construction and 25 arrangement on the transverse guide-plate or carriage-race of stopping mechanism for the knife-carriage, as hereinafter fully described.

In the drawings, Figure 1 is a front view of a part of a loom for weaving double pile fabric, 30 showing the arrangement of the grooved race-bar, the cords which reciprocate the knife-carriage, the circumferentially-grooved double-acting pulley-wheel, and cog-gearing connecting the latter with the rack-bar of the actuating-cam. Fig. 2 is a top view of the 35 grooved guide-plate or carriage-race and supporting-plate on which the pile fabric is severed. Fig. 3 is an enlarged top view of one end of the carriage-race, showing the position 40 of the knife-carriage, the mode of securing the cords thereto, the stopping device, and one of the cord friction-rollers. Fig. 4 is a detached vertical section of the velvet-delivering rollers, supporting-plate for the fabric, 45 carriage-race, knife-carriage, and knife. Fig. 5 is a side view in vertical section of one side of the loom from the inside, showing the upper cam to actuate the sharpening mechanism, the lower or knife-actuating cam and its

rack-bar and gearing to actuate the pulley-wheel, and the cords or bands leading from the latter to the knife-carriage. Figs. 6 and 7 are side and top views, respectively, of the cam and rack-bar by means of which the pulley-wheel is partially revolved in opposite directions to wind and unwind thereon cords attached to opposite sides of the knife-carriage, by means whereof the latter is reciprocated in the carriage-race.

The construction and operation of that part 60 of the mechanism of the loom which is used for weaving the double pile fabric in the manner stated I do not deem it necessary to describe, the same being well known in the art; and I shall therefore confine myself to showing and describing only that part of the mechanism of the loom involving my invention, and which performs the office of cutting the fabric laterally and producing therefrom two pieces 65 of pile fabric.

The framing supports between its sides A A', at the front of the loom, a supporting or cutting bar, L, which is a flat metal plate recessed at R, to admit of the insertion and vertical motion therein of the housing or frame 70 for the sharpening-rollers, which need not be described, as they may be of any known construction. Upon this plate or bar L the woven double pile fabric is received and over it the cutting-knife K'' passes. The bar L may, 75 however, be recessed in like manner at the other end, so as to admit of the insertion therein of a second and similar pair of sharpening-rollers, in order that the knife may be sharpened at each extremity of its lateral 80 travel and during its intervals of rest at each end of the race-bar, as hereinafter described.

Upper and lower velvet-rollers, F F, suitably mounted in the frame of the loom (see Fig. 4) take up the two pieces of severed pile 85 fabric T' T'', cut apart by the knife K'', from the two woven connected backings and draw forward the uncut double pile fabric T up to the traveling knife as it is delivered over and upon the supporting-bar L.

The rollers F F are geared together and actuated by a worm, to which motion is communicated from the picking-shaft or by other

appropriate means. Transversely across the front of the loom is arranged a grooved guide-plate or carriage-race, M, the position of which relatively to the supporting-bar L is shown in 5 Figs. 2, 4, and 5. This transverse guide-plate is grooved longitudinally to form a slide or race for the knife-carriage K, and is recessed at both ends to admit two friction pulley-rollers, N N', which have their bearings in the 10 guide-plate.

The cutting mechanism proper consists of a knife-carriage, K, which supports a knife-holder, K', in which the knife K'' is adjusted, the construction and arrangement of all of 15 which, however, are the same as heretofore employed and known in the art. (For example, see English patent of George Davies, No. 2,429, dated November 1, 1858.)

The knife-carriage moves laterally backward and forward in the groove of the guide-plate or race-bar M, being so reciprocated therein by means of two cords, E E', each of which passes over its respective friction-roller N or N' in the guide-race M. One cord, 20 E, is fastened to one side of the knife-carriage and passes thence over the friction-roller N, and the other cord, E', is fastened to the other side of the knife-carriage and passes from thence over the other friction-roller, N'. 25 It is at this point in the construction of the driving mechanism that my improvement begins. Heretofore all such looms were supplied with a pair of single-acting pulley-wheels, one on each side of the framing of 30 the loom, one wheel winding up one of said cords, E, while the other pulley was caused to revolve at the same time to unwind the other cord, E', attached to the other side of the knife-carriage, and vice versa, alternately, 35 and these pulley-wheels were usually mounted on a shaft extending from side to side to the loom-frame, which shaft was revolved by a rack-bar reciprocated by means of a cam, usually of complicated construction, connect- 40 ed directly or indirectly with the main driving-shaft. Such construction caused inequalities in the working parts, due to unequal wear and tension of the cords and pulleys and their driving-gear, and it is well known and mani- 45 fest that the result would be and is a corresponding inequality and imperfection in the reciprocating movement of the knife-carriage. 50

As the function performed by the knife-carriage must necessarily be very perfect and exact—the purpose of the knife being to divide one fabric into two single pile fabrics of equal height of pile by lateral severance of the connecting pile-threads incorporated into 55 both—the performance of this function by a single driving mechanism operating for both end-to-end movements of the knife-carriage will to a greater or less extent obviate the inequality of movement depending upon two 60 independent driving-pulleys, each operating only upon its side of the knife-carriage to

move it in one direction, and this result is aided in my improved loom by the use of a single positive-action cam, instead of the usual double cam, to actuate the driving-pulley; 70 hence I dispense with the usual pair of pulleys—one on each side of the loom—mounted on a shaft extending from side to side of the loom-frame, and substitute therefor a single double-acting pulley-wheel, D, grooved circumferentially and rigidly secured to a shaft, 75 12, which has its outer bearing in an arm, H, affixed to the frame of the loom.

The cords E E', above described, fastened to either side of the knife-carriage and passing over the friction-rollers N N', have their other ends fastened to the pulley D in the following manner: One cord, say E, on the side of the loom supporting the pulley D passes directly to the said pulley-wheel and has its 80 end knotted in the periphery thereof, while the other cord, E', fastened to the other side of the knife-carriage, passes over its appropriate friction-roller N', thence under the race-bar M to a second friction-roller, G, and 85 thence to and partially around the pulley-wheel D in a contrary direction from the other cord, E, and is in like manner fastened thereto. The said pulley-wheel has a movement given to it, which is a partial revolution, first 90 in one direction and then in the other, by means of the mechanism hereinafter described, and shown in Figs. 5, 6, and 7. This arrangement causes the knife-carriage K to be reciprocated in the grooved transverse 95 guide-plate or race-bar M, the to-and-fro movement in both directions being accomplished by a single actuating mechanism, the double-acting pulley-wheel D, with the described arrangement of the cords thereon, acting directly upon both sides of the knife-carriage 100 at the same time, the winding up of cord E drawing the knife-carriage K in one direction, while the simultaneous unwinding of cord E' permits of such movement, and vice versa, alternately, so that the wear and tension of the parts are evenly distributed on both sides of the knife-carriage, and the latter is thus reciprocated with greater uniformity and precision. 105

The mechanism for partially revolving the pulley-wheel D in either direction alternately, and which constitutes another and leading feature of my improvement, consists of a single cam, B, of the peculiar form shown in 110 Figs. 5, 6, and 7, and it is actuated by a cog-wheel, B'', which gears with a cog-wheel, C'', which, by means of its cam C, actuates the sharpening mechanism, as shown in Fig. 5. The cog-wheel C'' is mounted on the end of 115 a horizontal shaft having bearings in the frame of the loom. The cam B is securely fixed to the outer face of its actuating cog-wheel B'', around the end of the shaft B'', upon which said cog is mounted, said shaft 120 having its bearings in the frame of the loom and projecting slightly beyond the outer face 125 130

of the cog. This cam B operates to give reciprocating motion to the rack-bar B' by bearing alternately against the friction-rollers B''' and B^{IV}. The bar B' is provided with a cog-
5 rack, B^V, on a part of its upper surface, which gears with a small cog-wheel, D', secured to the same shaft as the cog D'', which in turn drives the cog D''', secured to the pulley-wheel D, and by these means the said pulley-
10 wheel is partially revolved in either direction alternately, and thus winds and unwinds successively the cords E E', one being wound up while the other is unwound, and vice versa, alternately, and so reciprocates the knife-car-
15 riage in the grooved guide-plate and severs the double pile fabric presented to the knife over and upon the supporting-bar L, as shown in Fig. 4, T representing the uncut double pile fabric, T' T'' being the two pieces cut
20 therefrom. The peculiar configuration of this cam B is of itself a novel feature of my invention. It is of the form of a segment of an annular plate with a central hole, thus showing two rounded sides, the smaller (being the inner one) fitting rigidly around the cog-shaft B⁶, and the larger (the outer side) being the part which comes in contact with the friction-rollers B''' B^{IV}. Now the operation of this
25 cam B, being arranged as shown, is such that, motion being given thereto by revolution of the shaft B⁶, moved by the cog-wheel B'', the rack-bar B' is reciprocated, and its rack B^V, acting on the cogs D' D'' D''', as described, causes a partial revolution of the pulley-wheel
30 D in either direction, as the bar B' may be moving backward or forward, depending upon the position of the cam B between the friction-rollers B''' B^{IV}, and by this cam being constructed and arranged as shown the rack-
35 bar B^V is at rest pending that part of the revolution of the cam B shown in the drawings, Figs. 5 and 6, as just completed, and therefore the knife-carriage is reciprocated along the groove of the guide-plate M, not by
40 a constant backward-and-forward motion, but between intervals of positive rest (which occur directly opposite the sharpening-rollers) at each end of its lateral travel on the grooved race-plate, equal to two picks of the loom at
45 50 each interval.

The second part of my improvement consists of an elastic stopping mechanism for the knife-carriage at each end of its lateral travel in the grooved race-bar M, as shown in Fig. 3, and described as follows: Two flanged cross-bars, 1 and 2, are secured to the plate M as bearings for a stopper-rod, 6, which has an enlarged end, 7, serving as a stopper for the knife-carriage. Encircling this stopper-
55 rod, on that part of it which is between the flanges of the cross-bars, are placed two pieces of rubber tubing, 4 and 5, and between them a metal band, 3, having a set-screw, 8, by which latter either piece of rubber tubing
60 65 may be compressed to or from either flange of the cross-bars 1 and 2. By this device,

which serves as an elastic cushion for the knife-carriage, I am also enabled to bring different parts of the knife-blade against the sharpening-rollers from time to time, as may be desired, by moving forward the rod 6 and shifting the position of the set-screw band 3 along the rod 6 to correspond, thereby bringing the enlarged end of the rod 6 in greater or less proximity to the extreme point of lateral travel of the knife-carriage, so that the sharpening-rollers may thus be brought to act on different portions of the knife-edge, according as the stopper-rod 6 may be adjusted laterally in the manner described, the sharpening-rollers being usually made circularly concave, or, if not so constructed in the first instance, assume that form from constant wear.

Having thus described my invention, what I claim as new, and desire to secure by Letters Patent, is—

1. The combination, with the frame A of the loom, a transverse race-bar, M, and a knife-carriage, K, of mechanism to reciprocate said knife-carriage in said race-bar, consisting of the double-acting circumferentially-grooved pulley-wheel D, located and supported on one side of the loom-frame, actuating-cords E E', connecting said knife-carriage on opposite sides thereof with opposite points on the periphery of said pulley-wheel, and mechanism to partially revolve said pulley-wheel in either direction alternately, substantially as described.

2. The combination, with the frame A, a transverse race-bar, a knife-carriage, and pulley mechanism to reciprocate the same in said race-bar, of actuating mechanism consisting of the shaft B⁶ and the cam B, constructed as a segment of an annular plate, with the smaller side thereof applied to said shaft, the rack-bar B', and gearing connecting the latter with said pulley mechanism, whereby the knife-carriage is reciprocated in said race-bar between intervals of positive rest at each end thereof and opposite the sharpening mechanism, substantially as described.

3. The combination, with the frame A and shaft B⁶, of the single cam B, constructed as a segment of an annular plate, with the smaller side applied to the said shaft, the rack-bar B', the double-acting pulley D, arranged to reciprocate the knife-carriage in both directions, gearing connecting said pulley-wheel with said rack-bar, the grooved race-bar M, knife-carriage K, and actuating-cords E E', connected with opposite ends of said knife-carriage and with opposite points on the periphery of said pulley-wheel, said parts being constructed, combined, and operating substantially in the manner and for the purpose set forth.

4. The combination, with the frame A of the loom, a transverse race-bar, M, a laterally-reciprocating knife-carriage, and mech-

anism to so actuate the same on said bar, of
elastic stopping mechanism for the knife-car-
riage, consisting of the rod 6, its bearings 1 and
2, elastic tubing 4 5, and set-screw band 3, con-
5 tructed and arranged substantially as set
forth.

In testimony whereof I have hereunto af-

fixed my signature this 21st day of Novem-
ber, A. D. 1884.

CHARLES PEARSON.
